UNITED STATES PATENT OFFICE.

ERNEST RUBES, OF JERSEY CITY, NEW JERSEY, ASSIGNOR OF ONE-HALF TO CHARLES F. REILLY, OF BROOKLYN, NEW YORK.

DESIGN FOR A SOUND AMPLIFIER.

Application filed May 31, 1924. Serial No. 9,763. Term of patent 3½ years.

To all whom it may concern:

Be it known that I, ERNEST RUBES, a citizen of the United States, residing at 320 Pavonia Avenue, Jersey City, in the county of Hudson, State of New Jersey, have invented a new, original, and ornamental Design for a Sound Amplifier, of which the following is a specification, reference being had to the accompanying drawing, forming part hereof, in which the figure is a perspective view of a sound amplifier showing my design.

I claim:

The ornamental design for a sound amplifier as shown.

ERNEST RUBES.
